WIRE ROPE SOCKET

George C. Soule, South Portland, Maine

Application August 17, 1942, Serial No. 455,061

4 Claims. (Cl. 24—126)

This invention relates to wire rope sockets and has for its main object to produce a socket strong enough to stand the breaking strain of the wire rope without itself suffering breakage or distortion and to produce it by a new and different process which results in a saving in the weight of steel used, in the weight of the finished product, and in the cost of producing it. A wire rope socket in accordance with my invention comprises a tubular portion sometimes designated as a "basket" having an internally tapered opening therethrough for receiving the spelter cone at one end of a wire rope, and an anchorage-engaging means, sometimes designated as "reins," extending from the opposed sides of the basket at the end thereof having the larger internal diameter. The anchorage-engaging means is so designed as to provide adjacent its junction with the tubular portion a pair of inwardly extending projections which function to maintain the spelter cone in the tubular portion. With either a closed or an open socket, the anchorage-engaging means or reins comprise a pair of spaced portions having aligned eyes. In the case of an open socket, the inwardly-extending projections are furnished by a pair of reinforcing plates fastened to the inner faces of said spaced portions and provided with eyes registering with the eyes of said spaced portions. In the case of an open socket, the inwardly-extending projections are furnished by the arms of a reinforcing plate of U-shape disposed between and fastened to the inner faces of said spaced portions and substantially filling the space therebetween, said arms being reduced and extended externally to overlap the juncture of the anchorage-engaging means with the tubular portion.

Prior to my invention the conventional method of making a wire rope socket was to make a solid steel drop forging in the general exterior shape of the finished article, and then by mechanical means to bore out from its interior a very large percentage of its weight in order to make room for the rope and the spelter cone which holds the rope in place.

The basis of my invention is the use of a pipe or tubing in which the center hole has already been made by an extrusion process without waste of steel, instead of using a solid bar which must first be drop-forged to shape and then bored out with excessive waste of steel.

Part of the economy of my socket over the conventional drop-forged socket is due to the elimination of boring and consequent waste of steel, and part of it is due to the fact that the

entire shell can be processed on lighter and less expensive machinery than the solid forging.

This economy is increased by the selection of seamless pipe or tubing which is in standard quantity production and is as much a tonnage steel mill product as is a bar.

Sockets made in accordance with my invention may always be made lighter as a finished product than drop-forged sockets because the drop-forging process distorts the design of the basket surrounding the spelter cone and requires it to be heavier than is necessary to match the strength of the rope in order that its outside diameter may equal the outside diameter of the forged reins.

In my invention the strength of the reins may be attained by pressing them thin and tall or high, whereas a drop-forged rein of the same cross sectional area must be thickened and made lower in order to draw out of the die that produces it.

The result of this is that for a given internal diameter the basket of a drop-forged socket will have an external diameter greater to the extent of the increased thickness of the two reins than on a socket in accordance with my invention. This of course adds to the weight of the forged socket and makes it a basically heavier design than mine.

The difference is a considerable one because the forged reins must approach the square in cross section, and have a 5 to 10° draft added on each side to enable them to be drawn out of the forging dies, while the reins of my socket need no draft and can be kept down to the thickness of the tubing and any strength sacrificed by such thinness can be compensated for by increasing the height without increasing the diameter of the basket. Thus my basket need be only thick enough and heavy enough to balance the strength of the rope while a forged basket must add thickness and weight beyond the strength of the rope in order to conform to a rein design necessitated by the forging process.

The principles of my invention are applicable to the production from seamless or other tubing of both closed and open wire rope sockets. With either type of socket, the center reinforcing plate for the reins of the closed socket or the side reinforcing plates for the reins of the open sockets are dimensioned to slightly overhang the spelter cone which supplements the spelter rings, if used, in retaining the cone in place, besides furnishing additional reinforcement for the socket.

Other advantages of my socket will appear as the description proceeds.

According to my invention I form my socket from a length of tubing, preferably a single length of seamless tubing. This is cut, opened and flattened at one end to form the socket reins, and is drawn at its other end to form the tapered socket basket, the reins and basket being afterwards suitably reinforced.

The equipment for the practice of my invention is simple and compact in design, is available at low cost, and may be operated by less skilled workmen than those needed for the large, expensive, and now-difficult-to-obtain drop-forging equipment.

In the accompanying drawings, I have illustrated my preferred method of making from seamless or other tubing both closed and open wire rope sockets. It will be understood, however, that various changes in procedural steps may be resorted to without departing from the spirit of or sacrificing any of the advantages of my invention.

In such drawings:

Fig. 1 is a perspective view of a closed wire rope socket in accordance with my invention.

Fig. 2 is a perspective view of a length of tubing from which such socket is fabricated.

Fig. 3 is a perspective view showing a preferred first step in the formation of the socket reins, such step involving cutting the tubing at one end to enable the reins to be formed.

Fig. 4 is an elevation, partly in section, illustrating a preferred next step in the formation of the reins, such step involving opening the tubing along the cuts shown in Fig. 3 and laying back the reins by means of the hydraulic press and forming tool shown in Fig. 4.

Fig. 5 is a perspective view of the tubing after it has been acted upon by the apparatus shown in Fig. 4.

Fig. 6 is a sectional view illustrating a preferred next step in the formation of the reins, such step involving flattening the split rein-forming halves of the tubing of Fig. 5 into the shape depicted in Fig. 7 by means of the hydraulic press shown in Fig. 6.

Fig. 7 shows the tubing after it has been acted upon by the apparatus of Fig. 6.

Fig. 8 shows the flattened reins of Fig. 7 being cut by a cutting torch to produce the eyes depicted in Fig. 9, it being understood, however, that the cutting torch of Fig. 8 is also used to trim off excess marginal metal from the reins.

Fig. 9 is a perspective view of the tubing after the cutting torch of Fig. 8 has trimmed the reins and formed the eyes therein.

Fig. 10 is a sectional view showing a preferred next step in the practice of my method, such step involving striking repeated blows on the basket end of the tubing shown in Fig. 9 by means of a trip hammer to draw the basket to the tapered shape shown in Fig. 1.

Fig. 11 is a perspective view showing the step of preparing a reinforcing plate for the socket, such plate being depicted in Fig. 12, and being afterwards assembled with the socket in the manner shown in Figs. 1, 15 and 16.

Fig. 12 is a perspective view of the cut and beveled reinforcing plate in readiness to be inserted between the reins of the socket and welded to the drawn basket of the socket.

Fig. 13 is a perspective view illustrating the step of finishing the socket, such step involving the use of a drilling press equipped with a reamer

and a nosing tool which respectively ream the basket to size and round off the bottom edge of the basket.

Fig. 14 is a plan view of an open wire rope socket made from seamless tubing in accordance with my method.

Fig. 15 is a longitudinal section of the closed socket shown in Fig. 1, particularly showing the welded-in spelter rings or projecting beads which engage the spelter cone and prevent it from slipping under strain in the socket.

Fig. 16 is a cross-section on the line 16—16 of Fig. 15.

Fig. 17 is a perspective view of the tubing from which the open socket of Fig. 14 is produced, said tubing having been cut at one end for the formation of the socket reins.

Fig. 18 is an elevation, partly in section, illustrating the next step in the formation of the socket reins, such step involving opening the tubing along the cuts of Fig. 17 and flattening the reins by means of the hydraulic press and forming tool shown in Fig. 18.

Fig. 19 is a perspective view of the tubing after it has been acted upon by the apparatus shown in Fig. 18, and

Fig. 20 is a longitudinal section through the completed open socket.

Referring to Figs. 1, 15 and 16 wherein I have indicated generally at 20 a closed wire rope socket made in accordance with my invention, the basket or tubular portion of such socket is designated at 21 and the anchorage-engaging means or reins at 22. Reins 22 extend as a pair of spaced portions from the opposite sides of the basket 21 at the end thereof having the larger internal diameter, and have alined eyes 22^a (see Fig. 9).

The basket is tapered to provide an internal socket 23 within which in some instances I may weld a plurality of spaced circumferentially disposed spelter rings or projecting beads 24. These engage the spelter cone (not shown) which is poured around the wire rope to retain it in place, and prevent the spelter cone from slipping under strain within the socket.

The basket and reins are reinforced by means of a reinforcing plate 26 which is dimensioned to longitudinally straddle the basket and substantially fill the space separating the reins. The plate 26 is preferably welded to the basket and reins, and is preferably of a length to overhang the spelter cone. Plate 26 is U-shaped (see Fig. 12). Its closed end defines an eye 26^a registering with the eyes 22^a of the reins 22. Its arms 26^b provide internal projection 26^c which prevent the spelter cone (not shown) in the basket 21 from being forced out of the adjacent end thereof by the stiffness of the rope when slack. Preferably such arms are reduced and extended as at 26^d to overlap the sides of the basket externally thereof for a substantial distance (see Figs. 1 and 15).

In producing my closed socket, I preferably start with a length of seamless tubing 27 (see Fig. 2) which, in the case of a 2 1/4" socket, may be approximately 19 1/2" long, 6" in diameter, and weights approximately 86 lbs.

I first cut one end of the tubing by means of a cutting torch or its equivalent to produce the cuts 28, 29 and 30 shown in Fig. 3. The cuts 28 are slots which begin at the upper end of the tubing at opposite sides thereof and terminate substantially half-way down the length of the tube in the holes 29. The cuts 30 define the lower ends of the eyes of the reins and assist the tubing

to open laterally when the slotted end of the tubing is acted upon by the expanding tool of Fig. 4 to lay back the reins.

In this operation, the tubing after being heated to the desired heat, is preferably subjected to the action of a forming tool 31 in a hydraulic press 32 which opens the slots 28 and expands the partially split halves of the tubing to the shape depicted in Fig. 5. During this operation, the lower end of the tubing is centered on the centering plug 33 of the press, stops 34 being provided near the upper end of the present guide to prevent the tubing from lifting out of the press when the tool 31 is raised.

The partly-formed tubing of Fig. 5 is next reheated to the desired heat, held between the dies 35 of a hydraulic press 36 (see Fig. 6) and the reins flattened into the shape depicted in Fig. 7. The press 36 has three superimposed dies, of which the top die is movable, the bottom die is stationary, and the center die is held loosely to the top die and acts as a spacer or anvil between the reins. Obviously, however, the reins may be flattened by other methods and by other apparatus.

The flattened reins are next trimmed of any excess marginal metal and the eyes 22^a formed therein. A preferred method of forming the eyes is depicted in Fig. 8 wherein a cutting torch 37 is shown at work.

In the interest of avoiding duplication of illustration, the trimming operation has not been illustrated, but it will be understood that in actual practice the torch may be first used to trim off excess marginal metal from the reins and then to cut the eyes. Preferably, the cutting torch which performs the trimming and eye-cutting operations is template-controlled.

The trimmed tubing with eyes formed in the socket reins is depicted in Fig. 9 in readiness for the formation of the socket basket. A preferred method of forming the socket basket is illustrated in Fig. 10 wherein the tubing, after having been again heated to the desired heat, is shown as being held as at 38 under a trip hammer 39 and subjected to repeated blows to draw the basket to the tapered shape illustrated in Fig. 1.

The socket is now ready to receive the reinforcing plate 26. In this step, I cut a reinforcing plate 26 of suitable dimension and weight from a block 40. Preferably, such plate is cut by means of a cutting torch such as indicated at 41 in Fig. 11. The torch may be template-controlled, if desired, or the plate may be hand-turned or die cut.

The finished plate 26, after beveling, is depicted in Fig. 12. In this condition, it is ready to be inserted between the reins and welded or otherwise fastened thereto and to the basket. (See Figs. 1, 15 and 16).

After the reinforcing plate 26 has been welded in place, the basket may be reamed to size and rounded at its bottom edge. I prefer to do this by means of the reamer 42 and nosing tool 43 of drilling press 44 shown in Fig. 13, although obviously it may be done by other methods and by other apparatus.

This completes the operation except for stress-relieving or galvanizing where required.

Depending on the ultimate use of the socket, it may or may not be desirable to provide the basket with the internal welded-in spelter rings or projecting beads 24 shown in Figs. 1, 15 and 16.

The open socket detailed in Figs. 14 and 20 includes a basket 21', reins 22', tapered internal

socket 23', spelter rings 24', if desired, and a pair of reinforcing plates 46 for the reins.

In producing such socket, I start with a length of seamless or other tubing 27' (see Fig. 17) which is first cut at one end as at 28', 29' to enable this end of the tubing to be expanded and the reins laid back and flattened.

This operation is preferably performed by the method and with the apparatus of Fig. 18, although it may obviously be performed by other methods and with other equipment. In this operation, the tubing of Fig. 17 is heated to the required temperature and then subjected to the action of a forming tool 31' in a hydraulic press 32' to thereby open the slots 28' and expand the split halves of the tubing to the flattened shape depicted in Fig. 19. During this operation, the lower end of the tubing is centered on the centering plug 33'.

10 The forming tool is raised and lowered by any suitable means (not shown) and the side walls of the press are pivoted at their lower ends at 47 to the base of the press and are urged inwardly towards each other at the proper time by means of 15 hydraulic rams 48 or the like.

20 When the reins have been flattened to the shape depicted in Fig. 19 by the apparatus of Fig. 18, they are trimmed in any suitable manner and the pin-receiving eyes or holes 49 cut therein, after 25 which the tubing is reheated to the proper temperature and the basket drawn.

25 In order to avoid duplication of illustration, this step has not been depicted, but it will be understood that it may be accomplished by means of a 30 trip hammer such as shown at 36 in Fig. 6.

35 The socket is now ready to receive the reinforcing plates 46. These are duplicates, and may be cut or cast in any suitable manner. Plates 46 are provided with eyes or holes registering with 40 the pin-receiving holes 49 of the reins. These plates follow generally the inside contour of the reins until the reins meet the basket 21', and extend internally into the basket as indicated at 45 46^a in Fig. 14 a distance sufficient to overhang the spelter cone. They are attached to the reins and basket in any suitable manner, as by welding, and they perform the double function of supplementing the strength of the tubing wall and reins and of furnishing increased bearing for the conventional socket pin at the eyes or holes 49.

50 My 2 1/4" open and closed sockets have been tested with the following results:

55 One of my 2 1/4" open sockets was attached to one end of a 2 1/4" 6 x 37 Blue Center Steel Rope with independent wire rope center, to the other end of which a standard test socket was attached. This was placed in a 2,000,000 pound Riehle testing machine, taken to a load of 317,000 lbs., and held for one hour under this stress. No weaknesses in the socketing or the socket developed, nor was there any evidence of distress in the socket after this test. The rope was finally broken at an ultimate strength of 424,700 pounds, but even at such load my socket showed no evidence of distress.

60 One of my 2 1/4" closed sockets was attached to one end of a 2 1/4" 6 x 37 Blue Center Steel Rope with independent wire rope center, to the other end of which a standard test socket was attached. This was placed in the 2,000,000 Riehle testing machine and the rope was tested to destruction developing a strength of 433,900 pounds. There was no evidence of distress in the socket after this test. Another of my sockets of quite similar design had been previously stressed at 317,000 lbs.

and held for 1½ hours without developing or showing any sign of distress. Such tests were ample to have developed any weaknesses in my socket.

I do not claim the spelter rings 24 as this concept is the invention of John B. Woodbury and is the subject of a separate application for patent filed Aug. 26, 1942, Serial No. 456,186 which has matured into Patent No. 2,347,229 granted April 25, 1944.

While I have disclosed my preferred methods for producing both the open and the closed sockets, it is to be understood that both the procedural steps and the equipment for carrying them out may be varied considerably without departing from the scope of my invention. Similarly, the sockets themselves are susceptible of various changes in form, proportion, size, and minor details of construction. All such changes are to be considered as within the purview of my invention, if within the limits of the appended claims.

What I therefore claim and desire to secure by Letters Patent is:

1. A wire rope socket, comprising a tubular portion having an internally tapered opening therethrough for receiving the spelter cone at one end of a wire rope, said tubular portion having an anchorage-engaging means extending from opposite sides of the tubular portion at the end thereof having the larger internal diameter, said anchor-

age-engaging means having adjacent its junction with the tubular portion inwardly extending projections for maintaining the spelter cone in the tubular portion.

5. The socket of claim 1, in which said anchorage-engaging means comprises a pair of spaced portions having alined eyes, and said inwardly extending projections are established by a pair of reinforcements fastened to the inner faces of said spaced portions and provided with eyes registering with the eyes of said spaced portions.

10. The socket of claim 1, in which said anchorage-engaging means comprises a pair of spaced portions having alined eyes, and said inwardly extending projections are established by the arms of a U-shaped member disposed between and fastened to the inner faces of said spaced portions and substantially filling the space therebetween.

15. The socket of claim 1, in which said anchorage-engaging means comprises a pair of spaced portions having alined eyes, and said inwardly extending projections are established by the arms of a U-shaped member disposed between and fastened to the inner faces of said spaced portions and substantially filling the space therebetween, said arms beyond said inwardly-extending projections being reduced and extended to externally overlap the juncture of the anchorage-engaging means with the tubular portion.

20. The socket of claim 1 in which said anchorage-engaging means comprises a pair of spaced portions having alined eyes, and said inwardly extending projections are established by the arms of a U-shaped member disposed between and fastened to the inner faces of said spaced portions and substantially filling the space therebetween, said arms beyond said inwardly-extending projections being reduced and extended to externally overlap the juncture of the anchorage-engaging means with the tubular portion.
